A. E. MacDONALD

SANITARY PIPE FITTING

Filed Dec. 29, 1923

UNITED STATES PATENT OFFICE.

ALEXANDER E. MACDONALD, OF WORCESTER, MASSACHUSETTS.

SANITARY PIPE FITTING.

Application filed December 29, 1923. Serial No. 683,346.

To all whom it may concern:

Be it known that I, ALEXANDER E. MACDONALD, a citizen of the United States, residing at Worcester, in the county of Worcester and State of Massachusetts, have invented a new and useful Sanitary Pipe Fitting, of which the following is a specification.

This invention relates to a pipe fitting for use at each floor of a building for connecting closets and other fittings with the soil pipe and properly venting the same.

The principal object of the invention is to provide a comparatively simple cast fitting for this purpose, which when connected up, will eliminate a large number of fittings, some of them special, and several feet of piping at each floor, thus economizing in the materials used and especially in the labor.

The invention involves a fitting constituting a combination **T** and **Y** and having special means to vent the side passage which forms part of the **Y**, the **Y** being horizontal at the top.

Reference is to be had to the accompanying drawings, in which

Fig. 1 is a view of the soil pipe and connections for three floors of a building with a preferred embodiment of my invention applied thereto on the first and second floors;

Fig. 2 is a side view of the fitting on enlarged scale;

Fig. 3 is a plan of the same; and

Fig. 4 is an end view.

I have shown the invention as applied to a soil pipe 10, although it can be applied to a stand pipe, drainage stack or the like. This soil pipe is shown as extending down through three floors of a building at each of which it is adapted to be connected with a closet, bath tub, sink and the like. I have shown the building as supplied with two of these fittings A, one at the first and one at the second floor. The fitting B shown at the third floor does not include all the features shown in the fittings A.

This fitting A comprises a vertical portion 11 provided with a vertical passage through it constituting part of the soil pipe and having hubs and openings at opposite ends for receiving sections of the soil pipe 10 in a well known manner. In the same vertical plane as the center of the upright part 11 is the center of a hub 12 which is designed to be connected with the outlet 13

from a closet. It will be seen that this part of the fitting constitutes a **T**, an interior passage from the hub 12 opening down into the upright passage in the part 11. The hub 12 is located between the ends of the upright section 11. This part of the device is vented by a vent passage 14 in a hub 15 terminating in the plane of the end hub 16 which constitutes the top of the upright portion 11 and which receives the lower end of the soil pipe 10 above. These parts are all substantially symmetrical with respect to the vertical plane which passes through the centers of the upright 11 and the hub 12.

Now to describe the **Y** part of the device, the throat 17, which leads from the upright part 11 to the hub 12 and which is curved in order to allow the water to flow down into the soil pipe, is provided with a side extension 20 having a passage therethrough. This passage communicates with the interior of the fitting and extends on a slight curve into the main channel thereof. It terminates in a hub 21 which has its terminal plane in the same vertical plane as the end of the hub 12. This hub 21 is provided for the purpose of connecting with a drain pipe 22 from the bath tub, sink, washing machine, or other fixture or fixtures which may be located in the same room or adjacent thereto. The difficulty comes in venting this part of the device so that when two closets are flushed on different floors a siphon will not be formed to empty one of the traps. This venting has been done heretofore by a separate pipe which had to be connected with the other vent pipe and involved a great deal of unnecessary expense as I have found.

For the purpose of venting this angular part 20 of the **Y**, I cast it when it is made with a hollow projection 23 extending practically from the outer side thereof clear over to the vent passage 14 and into which it extends. This hollow projection 23 thus permits air to enter it from all parts of the side passage 20 of the **Y** and delivers the air into the vent passage 14.

The vent pipe 25 extends up vertically from the vent passage 14 and is secured in the usual way in the hub 15. This passes up to a fitting 26 on the second floor above the second fitting A. The vent pipe 27 on this floor, which corresponds with the vent pipe 25 below, enters this fitting 26 and makes the venting a very simple matter.

In the case of the top floor the fitting B

does not necessarily have this additional venting feature because it cannot interfere with any discharge from any floor above. The vent pipe 25 extends clear up above the top floor and enters into the soil pipe through a fitting 28 as is usual.

As heretofore constructed there is the main vent pipe which has a fitting below the bottom floor connected to the soil pipe. 10 The main fitting is provided with a vent pipe which extends upwardly a short distance and is then connected by a fitting to the main vent pipe. This fitting I avoid, having only a single vent pipe on the first 15 floor and also avoid the extra fitting by which the old vent pipe was connected with the soil pipe including a T or Y below the fitting A. On the second floor all these fittings above mentioned are also avoided as 20 well as a cross for connecting what corresponds with the vent pipe 27 with the vent pipe 25, and with the other vent pipe from the fitting immediately below the fitting A on that floor. In addition to this there are 25 several elbows and other fittings that are eliminated. In fact altogether I count that I provide eight or nine fewer fittings on the second floor than have been necessary heretofore and do away with several feet 30 of vent pipe. The same saving is made on all floors between the first and top floors. I also simplify the soil piping by not having any vent pipe enter it at all directly.

In this way the necessary venting is secured all the way along the line and there is no necessity for putting any fittings, except the ones herein illustrated, into the soil pipe anywhere from the bottom to the top of the building. This is all done by 40 one casting at each floor and the vent pipe itself and its fittings are reduced in cost by a very large percentage without any danger of clogging the pipe. Yet the breaking of all the vacuums is prevented.

45 The parts above described can constitute the entire fitting if desired but in some cases I prefer to use the pipe 22 and side extension 20 for one purpose only, as for example the bath tub. In that case the pipe 50 30 from the sink and 31 from the wash tray drain into the branches of a double Y 32. This discharges directly down into a hub 33 integral with the cast fitting A. Below the hub 33 is a vertical branch 34 communicating with the main upright part 11 to discharge therethrough. In this case these 55 parts are vented directly by a vertical vent pipe 35 connected with the vent pipe 27 above.

60 Although I have illustrated and described only a single form of the invention I am aware of the fact that modifications can be made therein by any person skilled in the art without departing from the scope of the 65 invention as expressed in the claims. There-

fore, I do not wish to be limited to all the details of construction herein shown and described, but what I do claim is:—

1. As an article of manufacture, a fitting for a soil pipe or the like comprising a main hollow body having a branch extending therefrom for communication with the outlet of a water closet and provided with a side inlet passage communicating with the interior of the fitting for connection with a bath tub, wash basin or the like, the fitting having an air passage adapted to be connected with a vent pipe, and the side passage having an upwardly extending hollow projection to vent the side passage and communicating with the vent passage within the body of the fitting, whereby the entire fitting can be vented by a single vent pipe.

2. As an article of manufacture a T-Y fitting for a soil pipe or the like comprising a main vertical hollow body having a branch extending therefrom at right angles for communication with the outlet of a water closet and provided with a side inlet passage communicating with the interior of the fitting at the same level for connection with a bath tub, wash basin or the like, the fitting having communicating with the main portion thereof an air passage adapted to be connected with a vent pipe extending directly up from it, and the side passage having an upwardly extending hollow projection extending across it in order to vent the side passage all the way across and communicating with the vent passage within the body of the fitting.

3. As an article of manufacture, a T-Y fitting for a soil pipe or the like comprising a main vertical hollow body having a branch extending therefrom and provided with a side passage communicating with the interior of the fitting and an air passage adapted to be connected with a vent pipe extending up from it, and the side passage having an upwardly extending hollow projection to vent the side passage and communicating with the vent passage within the body of the fitting and located part way between the vertical portion of the fitting and the points at which the same is adapted to be connected with the waste pipe from the closet bowl and the like.

4. As an article of manufacture a T-Y fitting for a soil pipe or the like comprising a main vertical hollow body having a branch extending therefrom at right angles for communication with the outlet of a water closet and provided with a side inlet passage communicating with the interior of the fitting for connection with a bath tub, wash basin or the like, the fitting having, communicating with the main portion thereof, an air passage adapted to be connected with a vent pipe extending directly up from it, and the side passage having an

upwardly extending hollow projection extending across it in order to vent the side passage all the way across and communicating with the vent passage within the body of the fitting, the side passage being inclined downwardly toward the interior of the fitting, and the hollow projection being located horizontally above it and communicating with it substantially all the way across it.

5. In a soil pipe system, the combination with a vertical soil pipe, of a T-Y fitting at each floor, said fittings below the top floor each being provided with a hub for connection with a water closet, and a hub for connection with a sink, bath-tub or the like substantially at the same level, each fitting having a vertical air vent passage between the first named hub and the main 15 water passage down through it, for the purpose of venting that portion of the fitting, and a recess within the fitting communicating with said passage and arranged to conduct the air into said passage from all 20 points across the portion of the fitting which communicates between the second hub and the main vertical passage in the fitting, a

25

single vent pipe extending upwardly from the vent passage for venting both parts of the fitting, and a main vent pipe extending 30 upwardly along the soil pipe and connected at one point only with the first named hub.

6. As an article of manufacture, a fitting for a soil pipe or the like comprising a main hollow body having a branch extending 35 therefrom for communication with the outlet of a water closet and provided with a side inlet passage communicating with the interior of the fitting for connection with a bath tub, the fitting having an air passage 40 adapted to be connected with a vent pipe, and the side passage having an upwardly extending hollow projection to vent the side passage and communicating with the vent passage within the body of the fitting, said 45 fitting having a vertical side passage communicating with the main hollow body to receive the outlets from a sink and wash tray and vented by a vertical vent pipe extending directly up from it.

In testimony whereof I have hereunto affixed my signature.

ALEXANDER E. MACDONALD.
